UNITED STATES PATENT OFFICE.

JOEL McCOMBER, OF NEW YORK, N. Y.

SPINAL-DISTORTION APPARATUS.

SPECIFICATION forming part of Letters Patent No. 369,803, dated September 13, 1887.

Application filed May 23, 1887. Serial No. 239,053. (No model.)

To all whom it may concern:

Be it known that I, JOEL McCOMBER, of the city, county, and State of New York, have invented certain new and useful Improvements 5 in Spinal-Distortion Apparatus, of which the following is a full, clear, and exact description, reference being had to the accompanying drawings, illustrating the same.

This invention relates to that class of surgical appliances that are employed to reduce spinal curvature and to restore the spine, shoulders, and other affected parts of the body to their normal condition.

The present invention consists of a new and 15 improved pressure-applying spring apparatus which, by its simplicity of structure and adjustability in application, is adapted to correct spinal curvature and accompanying or similar displacements in the quickest and most 20 effective manner.

I will now proceed to describe the special form of apparatus that I have chosen to illustrate my invention and explain how this particular form can be modified.

25 Figure 1 shows a perspective view of the apparatus as constructed and adjusted for use to reduce an outward curvature of the spine. Fig. 2 shows the same in side elevation as applied to the body of a man, the dotted lines 30 representing the position of the parts before the apparatus is strapped down. Fig. 3 shows a rear view of the same; and Fig. 4 shows a plan view of the pelvic parts of the apparatus as they are while upon the person—that is, 35 this view represents what may be termed a "section" of a man's figure having the apparatus secured thereto, the section being taken just above the hips.

Referring to the views in detail, A and B 40 represent two flat metallic back-springs secured to a broad hip-spring, C. These springs A and B are made of any suitable material, being preferably broader at their lower ends than at their top ends. They are secured to 45 the hip spring C by any suitable means—as the rivets D—and may be adjustably secured thereto so as to be variously positioned thereon, as required by the demands of different cases. This hip-spring is constructed of thin 50 sheet metal, and is curved so as to partially approximate to the form of the back of a wearer. It is also bent over at its upper end

corners, E, so as to curve inwardly over the top of the hip-bones. The back-springs are crossed, as shown, and at their point of crossing are secured together by a screw, F, which is adapted to be removed, if required to change or adjust this point of crossing, either in a vertical or lateral direction. A pad, G, may be attached at this point to bear directly upon 60 the part to be treated and to cushion the springs. The top of the back-springs are curved so as to conform to the top of the shoulder, and they extend around the shoulders sufficiently to hook over and hold thereon. 65 To these ends of these springs are attached straps H, which are made of any suitable material, they usually being formed of some strong fabric or textile material which may or may not be elastic. These straps continue around 70 under the arms, and are secured to the back-springs at or near the point of their crossing.

I represents a broad abdominal belt attached to the ends of the hip-spring. This belt may be in two parts, as shown, or in one part, and 75 is provided with buckles or other suitable fastening devices for securing the belt around the person.

J are button-loops by which the trousers of the wearer may be supported; or these loops 80 may be otherwise arranged to support any other article of wear.

Fig. 2 shows an outward spinal curvature or protrusion and how the apparatus is applied thereto to reduce the same. The arms are 85 passed through the loops formed by the back-springs and the shoulder-straps, the back-springs passing just over the outer ends of the shoulders, as seen in Fig. 3. The lower part 90 of the apparatus will now spring from the body, about as seen in dotted lines in Fig. 2. The abdominal belt will now be secured around the person and the back-springs will thereby be bent inwardly, while the broad hip-spring will be bent to a form substantially that of the 95 person, thereby causing the back-springs to bear with an elastic lever-like action upon the protruding part as a fulcrum. By these means an elastic or yielding leverage pressure is exerted upon the protuberant portion of the spine, 100 that can be made to act by adjustment with more or less force, as the case may require. At the same time it will be observed that the upper portion of the trunk is free to move, being

unconfined or wrapped in with bandages or straps. Also, the shoulders, which in this kind of troubles are always bent forward, are subjected to a leverage pressure constantly 5 acting to throw them back, and, if deflected, to lift them into position and thereby expand and round out the shrunken chest or lung portions of the body; and, furthermore, the abdomen, which also protrudes, is subjected to 10 a gentle and sustaining compression, which lifts its contents and relieves the walls thereof from undue strain, thus permitting the muscles to contract and regain their normal place and tone.

15 In this latter connection it is to be specially noted that the broad hip-spring sustains an important function. Usually in similar apparatus for this kind of treatment it is the practice to employ bands or belts surrounding the 20 waist and located above the hip; but these really tend to still further extend the abdominal protrusion, as they bind in the muscles of the waist and by compression at that place press down and displace the pelvic contents.

25 The waist should be absolutely unrestricted in treating this class of distortion cases, so that the displaced pelvic contents can be raised to their natural position in the trunk. This is accomplished by my apparatus, the 30 broad abdominal belt being low enough to sustain and lift the pelvic contents, and there being no constriction at the waist to prevent their return to their natural position. To this end the hip-spring is shaped as described

35 and passes around to or near the front of the hip-bones, Fig. 2, so that the compression applied to the walls of the abdomen is not exerted upon the hips, and leaves them free to move unrestrained in any direction, Fig. 4.

40 The compression applied to the abdominal parts, therefore, is exerted only on the soft yielding walls thereof, and not upon or so as to impede or confine the waist or hips. This hip-spring is admirably adapted also to reduce

45 abdominal protrusion, whether accompanied by spinal distortion or not, in which case the back-springs may be used, (which, indeed, would be the best method,) or some other sup-

port therefor may be employed. It is also adapted to treating the special diseases of 50 women, and generally all troubles of abdominal displacements or weakness.

In the case of other forms of curvature the back-springs would be adjusted to cross at a point more to one side of or above or below 55 the place of crossing shown in Fig. 1, and the springs would be shortened or lengthened or made longer, one or both, as the position of the shoulders and the locality of the curvature might demand. So, too, for special cases 60 other parts may be added to this structure; but this structure would, however, constitute the basic or essential part of such apparatus. Thus the hip-spring is particularly well adapted to serve as the foundation support 65 for crutch devices or mechanism for applying to either or both shoulders a lifting or elevating pressure, and other braces or sustaining parts may be added to the apparatus to extend or localize its action; but in all such cases the 70 apparatus here shown and its general operation would be but modified without changing the principle of the invention.

It will be obvious that the parts composing this apparatus may be and usually would be 75 provided with some suitable textile or leather covering to protect the person of the wearer from contact with the metal parts.

What is claimed as new is—

1. In a spinal-distortion apparatus, the combination, with a hip-spring secured upon the back parts of the hips, of two back-springs attached to said hip-spring and crossing each other over or adjacent the curvature and extending to and secured upon the shoulders. 80

2. In combination, the hip-spring C, bent as shown at E, to extend inwardly over the hip-bones and provided with the belt I, the back-springs A and B, the pad G, and the shoulders-straps H, combined substantially as 85 set forth.

JOEL McCOMBER.
